(57) **CLAIM**

The ornamental design for a firearm barrel, as shown and described.

DESCRIPTION

FIG. 1 is a front perspective view of a first embodiment of our firearm barrel;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a back perspective view thereof.

The broken lines illustrate optional features of the firearm that form no part of the claimed design.
